CLAIM

The ornamental design for a pliers rack, as shown and described.

DESCRIPTION

FIG. 1 is a perspective view of a first embodiment of a pliers rack;

FIG. 2 is a first side view thereof;

FIG. 3 is a second side view thereof;

FIG. 4 is a third side view thereof;

FIG. 5 is a fourth side view thereof;

FIG. 6 is a bottom view thereof;

FIG. 7 is a top view thereof;

FIG. 8 is a perspective view of a second embodiment thereof; and,

FIG. 9 is a perspective view of a third embodiment thereof. The dashed broken lines in the figures illustrate portions of the pliers rack that form no part of the claimed design.

The pliers rack is shown with a symbolic break in its length. The appearance of any portion of the article between the break lines forms no part of the claimed design. The materials that may be visible between the jagged lines have been removed for clarity.
